BELLOWS SMOKING PIPE

Glenn Thomas Cathey, 1106 E. Saginaw,
Lansing, Mich. 48906

Filed May 2, 1974, Ser. No. 466,236

Term of patent 14 years

Int. Cl. D27—02

U.S. Cl. D27—3

FIG. 1

FIG. 2

FIG. 3

FIG. 4

FIG. 1 is a perspective view of a bellows smoking pipe showing my new design.

FIG. 2 is a front elevational view thereof.

FIG. 3 is a rear elevational view thereof.

FIG. 4 is a side elevational view thereof, the opposite side being substantially a mirror image thereof and as shown in FIG. 1.

The mouth tube is shown with broken away mid portion in FIGS. 1-4 for ease of illustration.

I claim:

The ornamental design for a bellows smoking pipe, as shown and described.
